UNITED STATES PATENT OFFICE.

JAMES B. McDEVITT, OF CHICAGO, ILLINOIS.

TELEPHONE-BOOTH.

1,274,914.

Specification of Letters Patent. Patented Aug. 6, 1918.

Application filed October 9, 1916. Serial No. 124,664.

To all whom it may concern:

Be it known that I, JAMES B. McDEVITT, a citizen of the United States, residing at Chicago, in the county of Cook and State 5 of Illinois, have invented new and useful Improvements in Telephone-Booths, of which the following is a specification.

This invention relates to telephone booths such as are provided in stores and other 10 places to give privacy to persons using the telephone and to exclude extraneous noises. As is well known, such booths are usually small, stuffy and badly ventilated, and the invention therefore has for its object to provide 15 a well ventilated and sanitary booth, which may be maintained on a more economical basis than booths of the ordinary type.

The object stated is attained by means 20 of a novel combination and arrangement of parts to be presently described and claimed and in order that the same may be better understood, reference is had to the accompanying drawings forming a part of this 25 specification.

In the drawings, Figure 1 is a front elevation of the booth; Fig. 2 is an enlarged cross-section thereof; Fig. 3 is a top plan view; Fig. 4 is an elevation of a series of 30 booths, partly in section, showing a modification, and Fig. 5 is an elevation, partly in section, showing another embodiment of the invention.

Referring specifically to the drawings, 35 denotes a booth provided with a door 6 as usual. In the top 7 of the booth is an opening in which is set and fixed a ventilator casing 8, open at the top and bottom. The bottom of the casing has an outstanding 40 marginal flange 9 which serves as a retainer to secure the casing in the opening. One end of the casing opens into the booth and the other end opens into the atmosphere. The upper portion of the casing is flared 45 and houses a fan 10 positioned horizontally and driven and supported by an electric motor 11. The fan blades are shaped to exhaust air from the inside of the booth. The motor is supported between two opposite 50 clamp plates 12 having depending bracket arms 13 secured to the top 7 of the booth on the outside thereof, by screws 14, with short coil springs 15 interposed between the booth top and the heads of the screws to absorb the vibration of the motor.

Near the bottom of the door 6, over a hood

17 on the latter, is an opening 16 to permit air to enter the booth when the door is closed. There will be a slight upward movement of air in the booth on account of 60 the draft between the bottom opening 16 and the top opening formed by the casing 8, but a positive circulation of air is assured when the exhaust fan 10 is running, drawing air into the booth from the bottom 65 and expelling it at the top. The booth is therefore kept well ventilated and also cooled in hot weather. Very little extraneous noise will enter the booth through the ventilating openings, and the telephone 70 may be used without the listener being disturbed by such noise.

In order that the fan 10 may be automatically controlled so that it will run only when a person enters the booth, and 75 stop when the person leaves the booth, the following mechanism has been provided:

Above the floor 18 of the booth, is located a vertically movable false floor or platform 18^a, the latter being hinged at one 80 end. The hinge consists of a rod 19 passing through the platform and protruding from the ends thereof, the protruding ends being journaled in bearings 20 on the floor 18 next to the side walls of the booth. The free 85 end of the platform rests on coiled springs 21 seating on the floor 18, said springs serving to normally maintain the platform elevated slightly from the floor. The springs are tapered coils so that they may telescope 90 completely when the platform is depressed.

A vertically slidable rod 22 is fixed to and rises from the free end of the platform 18^a, and has its upper end bent to overlie a button switch 23 controlling the circuit 95 of the motor 11 and also a lamp 24 in the booth, the conductor wires leading from the switch to the motor and to the lamp being shown at 25.

It will be evident that when a person enters the booth and steps on the platform 18^a, the latter is depressed, and through the rod 22 the switch 23 is operated to turn on the fan 10 and the lamp 24, and when the person steps off the platform on leaving the 100 booth the platform is elevated by the springs 21 to its normal position, and through the rod 22 the switch 23 is operated to turn off the fan and the lamp. The opening or closing of the door 6 of the booth does not affect 105 the switch, and the latter is controlled solely by the platform 18^a, so that there is no waste

of current, and the circuit being closed only when the platform is depressed and opened when the person steps off the same.

Where a series of booths arranged in proximity is employed, the structure shown in Fig. 4 may be used. Here, only the first booth in the series is provided with an exhaust fan 26 and a conduit 27 extends from the casing thereof over each succeeding booth and connected to the latter by branches 28 through the tops thereof. The current of air forced through the conduit 27 from the first booth will induce a draft in the succeeding booths. All of the booths will have the hereinbefore described switch-controlling means.

Fig. 5 illustrates another embodiment of the invention. Here each booth is connected at the top to a conduit 28 closed at one end, 20 and having its other end provided with an exhaust fan 30.

I claim:

1. The combination with a booth having an air inlet and an air outlet, of a vertically 25 tiltable floor section in the booth, an exhaust fan associated with the air outlet, an electric motor driving the fan, a switch controlling the motor circuit, said switch being separate and electrically isolated from the floor section, and a switch actuator operatively connected to the aforesaid floor section.

2. The combination with a booth having

an air inlet and an air outlet, of a false floor in the booth pivotally supported at one end, 35 springs supporting the other end of the floor, an exhaust fan associated with the air outlet, an electric motor driving the fan, a switch controlling the motor circuit, said switch being separate and electrically isolated from the floor section, and a switch 40 actuator operatively connected to the aforesaid floor section.

3. The combination with a booth, of a ventilating fan associated therewith, an electric motor driving the fan, a switch 45 controlling the motor circuit, a vertically tiltable floor section in the booth, said floor section being separate and electrically isolated from the switch, and a switch actuator 50 operatively connected to the aforesaid floor section.

4. The combination with a booth having a bottom air inlet and a top air outlet, of an exhaust fan associated with the air outlet, an electric motor driving the fan, a switch 55 controlling the motor circuit, a vertically tiltable floor section in the booth, said floor section being separate and electrically isolated from the switch, and a switch actuator 60 operatively connected to the aforesaid floor section.

In testimony whereof I affix my signature.

JAMES B. McDEVITT.
